Primary Examiner — Selina Sikder(74) *Attorney, Agent, or Firm* — Carr & Ferrell LLP**CLAIM**

The ornamental design for a voice controlled automation assistant, as shown and described.

DESCRIPTION

FIG. 1 is a front perspective view of a voice controlled automation assistant showing the new design;

FIG. 2 is a back view thereof;

FIG. 3 is a top view thereof;

FIG. 4 is a bottom view thereof;

FIG. 5 is a side view thereof from one side;

FIG. 6 is a side view thereof from the other side;

FIG. 7 is a perspective view thereof from the front; and,

FIG. 8 is a perspective view thereof from the back.

The broken lines showing the remainder of the voice controlled automation assistant are directed to environment. None of the broken lines form a part of the claimed design.
